[57] CLAIM

The ornamental design for a beverage bottle case, as shown and described.

DESCRIPTION

FIG. 1 is a top plan view of a beverage bottle case showing my new design;

FIG. 2 is a side elevation thereof;

FIG. 3 is an end elevation thereof;

FIG. 4 is a bottom plan view thereof.

FIG. 5 is a vertical cross sectional view thereof on line 5—5 of FIG. 1; and

FIG. 6 is a vertical cross sectional view thereof on line 6—6 of FIG. 2.

The side not shown is a duplicate of the side shown and the end not shown is a duplicate of the end shown.

FIG. 2

FIG. 3

FIG. 4

FIG. 5

FIG. 6
